CLAIM

The ornamental design for trunk liner, as shown.

DESCRIPTION

FIG. 1 is a front exploded perspective view of a trunk liner showing my new design;

FIG. 2 is a front perspective view thereof;

FIG. 3 is a top plan view thereof;

FIG. 4 is a front perspective view of a trunk liner showing my new design, the difference being the placement of the dividers at the narrower end;

FIG. 5 is a top plan view thereof;

FIG. 6 is a bottom plan view thereof;

FIG. 7 is an end elevational view thereof;

FIG. 8 is an opposite end elevational view thereof;

FIG. 9 is a left side elevational view thereof; and,

FIG. 10 is an opposite side elevational view thereof.

FIG.1.

FIG. 2.

FIG. 3.

FIG.4.

FIG.5.

FIG.6.

FIG.7.

FIG.8.

FIG.9.

FIG.10.
